Int. Cl. D21—02

U.S. Cl. D34—15

The figure is a perspective view of the toy spinning top showing my new design. The figure in the cab not shown is similar to the figures in the cabs shown. The characteristic feature of my design resides in the particular multi-legged canopy and rider figures in combination with the toy spinning top, all as shown.

I claim:

The ornamental design for a toy spinning top, as shown and described.
